[57] CLAIM

The ornamental design for a vehicle polishing apparatus, as shown and described.

DESCRIPTION

FIG. 1 is a perspective view of a vehicle polishing apparatus showing my new design.

FIG. 2 is a right side elevational view, the left side being a mirror image thereof.

FIG. 3 is a right end elevational view thereof.

FIG. 4 is a left end elevational view thereof.

FIG. 5 is a top view thereof.

The upwardly projecting post is shown fragmentarily in FIG. 1 for convenience of illustration. The brush element has been shown fragmentarily in FIG. 2 in order to fully disclose the rear wheel.
